UNITED STATES PATENT OFFICE.

JAMES BOUCEK AND JAMES HALICK, OF CLEVELAND, OHIO, ASSIGNEES OF ONE-THIRD
TO JOSEPH TREFNEY, OF CLEVELAND, OHIO.

FURNACE.

Application filed November 5, 1923. Serial No. 348,424.

This invention relates to furnaces, especially designed for the enameling of iron, steel and the like and for the treatment of ceramic ware and similar articles, the general object of the invention being to so construct the furnace that the maximum amount of heat will be secured from the minimum amount of fuel and also to distribute the heat evenly over the whole furnace.

This invention also consists in certain other features of construction and in the combination and arrangement of the several parts, to be hereinafter fully described, illustrated in the accompanying drawings and specifically pointed out in the appended claims.

In describing our invention in detail, reference will be had to the accompanying drawings wherein like characters denote like or corresponding parts throughout the several views, and in which:

Figure 1 is a sectional view on line 1—1 of Figure 2.

Figure 2 is a sectional view on line 2—2 of Figure 1.

Figure 3 is a sectional view on line 3—3 of Figure 2.

Figure 4 is a sectional view on line 4—4 of Figure 2.

Figure 5 is a sectional view on line 5—5 of Figure 2.

Figure 6 is a sectional view on line 6—6 of Figure 1.

In these views, 1 indicates the oven or baking chamber, the walls 2 of which are spaced from the interior walls 3 of the furnace. A web or wall 4 extends longitudinally above the oven and connects the top wall of the same with the top interior wall of the furnace and divides the space between the oven and the interior walls of the furnace into two passages 6 and 7, the front ends of which are in communication with the combustion chamber 8 by the inlet ports 9, and the outer ends of these passages are in communication with the vertical space 10 at the rear of the oven, which leads the products of combustion to the outlet 11 at the rear of the furnace which is to be connected with a chimney. Baffles 12 are arranged in the passages 6 and 7 for causing the products of combustion passing through the same to take a zigzag course along the sides and top of the oven, thereby thor-

oughly heating the same. The oven is separated from the combustion chamber 8 by a double-wall 13 which will prevent quick cooling of the floor of the oven when the door of the oven is open. This will prevent cracking of the floor.

The combustion space 14 is arranged at the rear end of the combustion chamber 8 and the fuel is admitted to the said space through the opening 15. The chamber 8 is divided into a plurality of longitudinally extending passages 16 and laterally extending passages 17 which intersect the passages 16. Some of the passages 17 are in communication with the sides of the combustion space 14. The last two passages 17 are in communication with the ports 9.

An air chamber 18 is arranged below the combustion chamber 8 and has its rear end in communication with the combustion space 14 through the port 19. A pair of air passages 20 have their inner ends connected with the chamber 18 and their outer ends passed through the rear wall of the furnace, where they are provided with the valve device 21 for controlling the flow of air into the passages. One of these passages is arranged at each side of the air chamber.

From the foregoing it will be seen that the air, entering the device, is heated from the heat radiated from the bottom of the combustion chamber so that it will enter the combustion space 14 in a highly heated condition and thus improve the combustion of the fuel entering through the opening 15. The products of combustion, circulating through the passages 16 and 17, will highly heat the bottom of the oven or chamber 1 to a uniform degree. Then the products of combustion circulate around the sides and top and the end of the oven, the gases flowing in a zigzag path around the oven before escaping to the chimney through the exhaust 11. Thus the oven will be highly heated with the minimum amount of fuel and the heat is evenly distributed over the whole oven. By heating the air before it reaches the combustion chamber, perfect combustion of the fuel is secured. The fuel used may be either gas, oil or coal, but when coal is used, the combustion space must be formed as a fire box.

It is thought from the foregoing description that the advantages and novel features of our invention will be readily apparent.

We desire it to be understood that we may make changes in the construction and in the combination and arrangement of the several parts, provided that such changes fall within the scope of the appended claims.

What we claim is:—

1. A furnace of the class described comprising an oven having its sides and top and back spaced from the interior walls of the 10 furnace, a combustion chamber below the oven and having its front end in communication with the space between the oven and the interior walls of the furnace, baffles in the said space for causing the products of 15 combustion to pass in a zigzag path to the rear of the oven, exhaust means at the rear of the furnace in communication with the space at the rear of the oven, a combustion space at the rear of the combustion chamber, 20 means for introducing fuel into said space, an air chamber below the combustion chamber having its rear end in communication with the combustion space, a passage extending from the front end of the air chamber 25 through the rear of the furnace for admitting air into the air chamber and means for controlling the entrance of air into said passage.
2. A furnace of the class described comprising an oven having its sides and top and back spaced from the interior walls of the 30 furnace, a combustion chamber below the oven and having its front end in communication with the space between the oven and the interior walls of the furnace, baffles in the said space for causing the products of 35 combustion to pass in a zigzag path to the rear of the oven, exhaust means at the rear of the furnace in communication with the space at the rear of the oven, a combustion space at the rear of the combustion chamber, 40 means for introducing fuel into said space, an air chamber below the combustion chamber having its rear end in communication with the combustion space, a passage extending from the front end of the air chamber through the rear of the furnace for admitting air into the air chamber, means for controlling the entrance of air into said passage and baffles 45 in the air chamber for causing the air to take a zigzag path through the same.
3. A furnace of the class described comprising an oven having its sides and top and back spaced from the interior walls of the 50 furnace, a combustion chamber below the

oven and having its front end in communication with the space between the oven and the interior walls of the furnace, baffles in the said space for causing the products of combustion to pass in a zigzag path to the rear of the oven, exhaust means at the rear of the furnace in communication with the space at the rear of the oven, a combustion space at the rear of the combustion chamber, 55 means for introducing fuel into said space, an air chamber below the combustion chamber having its rear end in communication with the combustion space, a passage extending from the front end of the air chamber through the rear of the furnace for admitting air into the air chamber, means for controlling the entrance of air into said passage, baffles in the air chamber for causing the air to take a zigzag path through the same and said combustion chamber being composed of 60 longitudinally extending passages and transversely extending passages intersecting the longitudinal passages.

4. A furnace of the class described comprising an oven having its sides, top and rear spaced from the internal walls of the furnace, exhaust means at the rear of the furnace connected with the space at the rear of the oven, baffles in the space at the sides and top of the oven for causing the products of combustion to take a zigzag path through said space, a combustion chamber located below the oven, a double wall separating the oven from the said space, a combustion space at the rear end of the combustion chamber, said combustion chamber being composed of longitudinally extending passages and transversely extending passages, means for introducing fuel into the combustion space, an air chamber located below the combustion chamber and having its inner end in communication with the combustion space, baffles in the air chamber for causing the air to take a zigzag path through the same, an air passage at each side of the air chamber and connected with the front end of the same, said air passages passing through the rear of the furnace and valve means for controlling the flow of air into the said passage.

In testimony whereof we affix our signatures.

JAMES BOUCEK.
JAMES HALICK.
